UNITED STATES PATENT OFFICE.

MILTON FRANK JOBES AND CLARENCE A. SNOW, OF EAST RANDOLPH, NEW YORK.

SEED-DISPLAY CABINET.

No. 926,809.

Specification of Letters Patent.

Patented July 6, 1909.

Application filed October 3, 1908. Serial No. 456,005.

To all whom it may concern:

Be it known that we, MILTON FRANK JOBES and CLARENCE A. SNOW, citizens of the United States, residing at East Randolph, in the county of Cattaraugus, State of New York, have invented a new and useful Seed-Display Cabinet, of which the following is a specification.

This invention relates to cabinets for use 10 in shipping and displaying seeds and other merchandise contained in packages.

The object of the invention is to provide a cabinet consisting of nested trays designed to be shifted relative to one another so as 15 to assume a stepped relation when it is desired to display the contents of the cabinet, said sections being also designed to collapse so as to nest within the main or body portion of the cabinet, and thus occupy the 20 minimum space.

Another object of the invention is to provide simple means whereby the sections of the cabinet will be automatically locked when the cabinet is extended for display 25 purposes.

A further object is to provide a cabinet so constructed that two of said cabinets can be conveniently secured together and transported as a crate without danger of injury 30 to or loss of the contents.

With these and other objects in view the invention consists of certain novel details of construction and combinations of parts hereinafter more fully described and pointed out in the claims.

In the accompanying drawings the preferred form of the invention has been shown.

In said drawings:—Figure 1 is a plan view of the cabinet. Fig. 2 is a transverse section therethrough, one half of the cabinet being shown extended, while the other half is collapsed. Fig. 3 is a transverse section through the portions of two cabinets secured together to form a crate.

Referring to the figures by characters of reference 1 designates a pedestal of any suitable construction and proportions and having a stud 2 extending therefrom and constituting a pivot for the body 3 of the cabinet.

This body is preferably formed of a rectangular box of wood or other material and has a central opening 4 into which the stud 2 extends. Secured within the corner portions of the body 3 are retaining brackets 5, having

inwardly curved flanges 6 at their upper 55 edges and which are preferably flush with the corresponding edges of the body.

Arranged upon the center of the bottom of the body 3 is a small tray 7 preferably rectangular in outline and having a bail 8 or 60 other suitable handle connected thereto. This tray is surrounded by another tray 9 having an opening 10 therethrough within which the tray 7 is mounted. The inner wall 11 of this tray 9 extends upwardly from 65 the edges of the opening 10 and is considerably higher than the walls 12 of the middle tray 7. Stop flanges 13 extend from the wall 11 and overhang the wall 12, so that the tray 7 can be raised a predetermined distance between the walls 11 and will ultimately come into contact with and be stopped by the flanges 13. Another tray 14 surrounds the tray 9 and has a central angular opening 15 in which said tray 9 is mounted. The inner wall 16 of the tray 14 extends 70 upwardly from the edges of this opening and is also provided with stop flanges 17 designed to overhang the short outer wall 18 of tray 9. Any desired number of trays may be provided and they are all arranged in the manner hereinbefore described. The outer tray 19 has a short outer wall 20 designed to be limited in its movement by the corner bracket 6, heretofore referred to. Each of 75 the short walls of the trays is provided with one or more oppositely disposed spring catches 21 designed, when the nested trays are raised, to spring into engagement with the upper edges of the inner walls of the next 80 adjoining trays. It is of course to be understood that those of the catches upon the outer tray 19 engage the wall of the body 3. Each of the trays is subdivided by means of partitions 22 into separate compartments, 85 each compartment being designed to receive a number of packages of seeds or other merchandise.

When it is desired to shift cabinets such as here described the trays are all nested as 100 shown at the right of Fig. 2, and the various compartments therein are filled with packages. The compartments are then covered with a layer of card-board 23, or other material, after which another filled cabinet is 105 inverted and placed upon this card-board. The two cabinets can then be secured together by means of a strip or strips 24 nailed

or otherwise fastened thereto. Two cabinets connected in this manner have been shown in Fig. 3.

When it is desired to use the cabinet for display purposes the same is placed upon the pedestal 1 and the inner tray 7 is pulled upwardly by means of the bail 8. When this tray comes into contact with the inwardly extended flanges 13 of the next adjoining tray it will pull upwardly on said tray and this movement will be transmitted intermittently from the inner to the outer trays until all of them have been elevated above the body 3. It is of course to be understood that as soon as one tray becomes extended as far as it will go the hooks or catches 21 carried thereby will spring into engagement with the adjoining wall of the next tray. Obviously therefore as soon as all of the trays have been pulled upwardly they will remain in extended position, and the contents of all of the trays will be supported in stepped relation where they can be conveniently seen. To close or collapse the cabinet the various catches 21 are disengaged from the walls engaged by them and the trays will therefore move downward by gravity into the body.

It will be seen that this device is very simple, durable and efficient, and that the same is advantageous not only because of the fact that it constitutes means whereby all of the contents thereof can be conveniently seen, but also because it can be collapsed into a compact body and two of them can be assembled together to form a crate so as to enable these devices to be shipped at comparatively slight cost and without danger to the contents thereof.

What is claimed is:—

- 40 1. A cabinet comprising a body, a series of homocentric nested trays therein, and means carried by each tray for automatically engaging the wall of the adjoining tray to support the trays in stepped relation.
- 45 2. A display cabinet comprising a body, a series of homocentric nested trays slidably mounted within the body, means for facili-

tating the elevation of the middle tray, and means carried by the trays for automatically engaging the adjoining trays to lock the said trays in elevated position.

3. A display cabinet comprising a body, a series of homocentric nested trays therein, each tray having an inner and an outer wall, means carried by the outer wall of each tray for automatically engaging the inner wall of the adjoining tray when the trays are elevated to support said trays, and means for limiting the movement of the trays relative to one another.

4. A display cabinet comprising a body, a series of nested trays within the body, each tray having an inner and an outer wall, all of said trays surrounding the innermost tray, means carried by each tray for automatically engaging the wall of the adjoining tray to support the trays in elevated positions, and means upon the trays for limiting the relative movement thereof.

5. A display cabinet consisting of a series of homocentric nested trays, and means carried by each tray for automatically engaging the adjoining tray to support all of the trays in stepped relation.

6. A display cabinet consisting of a series of nested trays, each tray having a rectangular series of compartments therein, the compartment of each tray surrounding the next inner tray, means carried by the trays for limiting the relative movements of the trays, and means upon the trays for automatically engaging the adjoining trays to lock the same in stepped relation.

In testimony that we claim the foregoing as our own, we have hereto affixed our signatures in the presence of witnesses.

MILTON FRANK JOBES.
CLARENCE A. SNOW.
